TALKING MACHINE

Herace Leopold Tucker Buckle, Buckinghamshire, and Harry Archibald Thompsett, Ealing, London, England, assignors, by mesne assignments, to Radio Corporation of America, New York, N. Y., a Corporation of Delaware

Application December 21, 1929, Serial No. 415,754,
and in Great Britain January 19, 1929

16 Claims. (Cl. 274—2)

This invention relates to improvements in talking machines and more particularly to talking machines of the kind in which a hinged lid or cover is utilized to form part of the sound amplifying horn.

The invention is mainly directed to the provision of a machine which, though small and compact when closed, possesses when ready for playing, the advantages of an amplifier with a large outlet opening, and it is particularly applicable to talking machines of the kind known as portable machines.

In the machine according to the invention, the horn mouth is formed by the hinged lid and a plate which is mounted to move, as the lid is opened and closed, about a different axis than that of the lid, the plate and the lid in the closed position lying closer together than they do in the open positions. The plate may extend across the full width of the lid and, with a view to providing a horn mouth of large depth from back to front, the plate may be furnished with side wings and the sides of the lid may be made deeper than has been the practice hitherto, the lid sides extending, in the closed position, a considerable distance below the level of the turntable and even to the level of the bottom of the box.

The back of the casing may be formed in one piece, fixed with regard to the box portion and extending from the bottom of the box to the top of the lid when closed, and the lid may be hinged to move about an axis situated at the upper edge of the back of the casing, while the plate which, together with the lid forms the horn mouth, is hinged to move about an axis forward of and spaced from the lid hinge but situated close to the plane of the lid top when closed.

The invention is illustrated, by way of example, in the accompanying drawings in which Fig. 1 is a view in perspective showing the machine ready for playing.

Fig. 2 is a plan view of the machine with the lid and motor board removed and showing the arrangement of the amplifying horn.

Fig. 3 is a view in sectional elevation taken on the line 3—3 of Fig. 2, showing the lid in open position, and

Fig. 4 is a similar view showing the lid in closed position.

Referring to the drawings, a box 1 is provided having front and side walls 2 and 3 of less height than those of machines of usual type and a rear wall 4 equal in height to the total height

of the case when closed. In the box is mounted a metal or other amplifying horn 5 with its inlet and outlet ends 6 and 7 towards the rear of the box, the horn 5 following a substantially circular path within the box, as clearly shown in Fig. 2, so that a space 8 is left in the centre to house the driving motor not shown. Packing pieces 9 are provided in the front corners of the box 1 and a side plate 10 covers the V-shaped space indicated at 11 in Fig. 2.

The outlet end 7 of the horn 5 is equal in width to the full inner width of the box 1 and extends upwardly, as clearly shown in Figs. 1, 3 and 4, to substantially the level of the upper edge of the rear wall 4 of the box 1. The inlet end 6 of the horn 5 is arranged to pass through the side wall 12 of the horizontal portion of the horn near the outlet end and to extend upwardly as shown at 6 in Figs. 3 and 4 within the outlet end 7 and finally through the front wall 13 of the outlet end 7 where it projects forwardly and is connected through a suitable bearing joint 14 with the sound arm 15.

On the upper surface of the horizontal portion of the horn 5 and to the side plate 10 is secured a metal or other plate 16 which serves as a motor board to support the motor (not shown) arranged in the space 8 surrounded by the horn. The usual turntable 17 is provided above the motor board.

To the upper edge of the rear wall 4 of the box 1 is hingedly connected the lid formed of a top 18, front and side walls 19, 20 but no back wall, the hinge being connected with the rear edge of the top 18. The front and side walls are of such a height as to extend to the upper edges of the shallow walls 2, 3 of the box when the case is closed, so that the amplifying horn 5, motor board 16, turntable 17, sound arm 15 and other parts are satisfactorily enclosed.

To the upper edge of the front wall 13 of the upwardly extending outlet end 7 of the amplifying horn is hingedly connected a metal plate 21 which extends across the full width of the lid and along from one third to one half, for example, of the length of the lid.

The hinged plate 21 is provided with narrow side wings 22, which lie parallel to the side walls 20 of the lid and are movable, together with the plate 21, relative to the side walls 20. The wings are furnished with stop pins 23 which engage in slots 24 in the side walls 20 of the lid to limit the movement of the plate 21 with regard to the lid and therefore the extent to which the lid can be opened. In the open posi-

tion of the lid, the plate 21 and its wings 22 together with said lid form an extension of the upwardly directed portion 7 of the amplifying horn.

5. A series of notches 25 may be provided in the slots 24 with which the stop pins 23 may be engaged to vary the open position of the lid and hinged plate 21 and therefore the size and direction of the horn mouth.

10. The line of juncture of the side walls of the box 1 and the lid may be shaped as shown in the drawings to provide the most desirable shape for the horn mouth. The side walls 20 of the lid are shown as being deepest at a point one third 15 to one half the length of the lid away from the rear edge so that a horn mouth of large depth may be obtained with wings 22 of small width on the plate 21.

When the lid is closed, hinged plate 21 is 20 moved down about its hinge on wall 13 into the position shown in Fig. 4 where it lies close to the wall 18 of the lid, the hinge of the plate 21 in the case illustrated being in contact with the underside of the wall 18 of the lid.

25. The space between plate 21, the motor board 16 and wall 13 when the machine is closed may be utilized to house the sound arm 15 and sound box and an aperture 26 may be provided in the motor board to receive the sound box to retain 30 the latter and the sound arm 15 in fixed position as shown in Fig. 4 during transit.

We claim:

1. In a talking machine, a base, a cover hinged to said base, a plate pivoted to said base and cooperating with said cover to form a horn extension, and means connecting said cover and said plate for simultaneous movement when the cover is moved.

40. 2. In a talking machine, a base, a cover hinged to said base, a plate pivoted to said base and cooperating with said cover to form a horn extension, and means connecting said cover and said plate for movement of one relative to the other when said cover is moved.

45. 3. In a talking machine, a base, a cover hinged to said base, a plate pivoted to said base and cooperating with said cover to form a horn extension, and means connecting said cover and said plate whereby said plate occupies a position adjacent said cover when in closed position, and a position separated from said cover when in open position.

50. 4. In a talking machine, a base, a cover hinged to said base, a plate pivoted to said base and cooperating with said cover to form a horn extension, and means connecting said cover and said plate whereby said plate occupies a position nearer to said cover in closed position than in open position.

55. 5. In a talking machine, a base, a cover hinged to said base, a plate pivoted to said base and cooperating with said cover to form a horn extension, and means connecting said cover and said plate for simultaneous movement from open to closed position, said means being adapted to retain said horn extension in open position.

60. 6. In a talking machine, a base, a cover hinged to said base, a plate pivoted to said base and cooperating with said cover to form a horn extension, and means connecting said cover and said plate for simultaneous movement from open to closed position, said means being adapted to retain said horn extension in any one of a plurality of intermediate positions.

65. 7. In a talking machine, a base, a cover hinged

to said base, a plate pivoted to said base with its pivotal axis spaced from the hinge axis of said cover, and means connecting said plate with said cover whereby said plate is movable with said cover about an axis different than that of the 80 cover, said plate and cover cooperating to form a horn extension when in any position except fully closed position.

8. In a talking machine, a base, a cover hinged to said base, a plate pivoted to said base with its 85 pivotal axis spaced from the hinge axis of said cover, and means connecting said plate with said cover whereby said plate is movable with said cover from open to closed position about an axis different than that of the cover, the pivotal axis 90 of said plate being substantially in the same plane as the plane of the cover when in closed position.

9. In a talking machine, a base, a cover hinged to said base, a plate pivoted to said base with its 95 pivotal axis spaced from the hinge axis of said cover, and means connecting said plate with said cover whereby said plate is movable with said cover from open to closed position about an axis different than that of the cover, the 100 pivotal axis of said plate being parallel to the axis of the cover and in substantially the same plane as the plane of the cover when in closed position.

10. In a talking machine, a base, a cover 105 hinged to said base and having a top and side walls, a plate pivoted to said base and forming with said top and said walls a horn extension, said plate being shorter than the top, whereby a horn opening is provided, and means connecting said cover and said plate for simultaneous movement when said cover is moved.

11. In a talking machine, a base, a cover hinged to said base and having a top and side walls, said side walls being of greatest width 115 intermediate their ends, and a plate pivoted to said base and forming with said top and side walls a horn extension, said plate extending substantially to the point of greatest width of said side walls, whereby a horn opening of 120 maximum dimensions is formed.

12. A portable phonograph comprising a base, a horn mounted in said base and having an upwardly extending portion, a cover hinged to said base, a plate pivoted to said upwardly extending 125 portion and cooperating with said cover to form an extension for said horn, and means connecting said cover and said plate for relative movement when said cover is moved.

13. A portable phonograph comprising a base, 130 a horn mounted in said base and having an upwardly extending portion, a cover hinged to said base, a plate pivoted to said upwardly extending portion and lying adjacent said cover when in closed position, and means connecting said cover 135 and said plate for relative movement, whereby said plate is separated from said cover when said cover is moved to open position to provide an extension for said horn when the cover is in open position.

14. In a portable phonograph comprising two hingedly connected sections, a pivoted member on one of said sections and means on the other of said sections cooperating with said pivoted member to maintain said sections in open position, said pivoted member cooperating with said other section to form a horn extension.

15. In a talking machine, a base, a cover hinged to said base, and a plate pivoted to said base and movable with said cover about an axis 140

different than that of the cover, said plate and cover cooperating to form a horn extension.

16. In a talking machine, a base, a cover hinged to said base, and a plate pivoted to said 5 base and movable with said cover from open to closed position about an axis different than that

of the cover, the pivotal axis of said plate being nearer to said cover when said cover is in closed position than when said cover is in open position.
